UNITED STATES PATENT OFFICE

PAUL M. KUEHN, OF BALTIMORE, MARYLAND, ASSIGNOR TO THE BARTLETT HAYWARD COMPANY, OF BALTIMORE, MARYLAND, A CORPORATION OF MARYLAND

CENTRIFUGAL SCRUBBER

Application filed May 31, 1927. Serial No. 195,557.

This invention pertains to that type of liquid and gas contact apparatus commonly known in the art as centrifugal scrubbers. Such scrubbers have long been in use and 5 probably the best known and most successful form is that commonly designated as the Feld scrubber shown generally in U. S. Letters Patent to Walther Feld Nos. 829,261, 940,103 and 983,037.

10 The structure of the present invention is of the same centrifugal type but is so constructed and arranged as to produce more efficient results and this with the expenditure of less power or energy to actuate the 15 same.

Aside from the advantage just expressed the invention has for its further object the production of a pumping element which will effectively elevate the liquid from the pan 20 below said element and initially spray or break up the liquid as it is thrown outwardly by centrifugal action prior to its passage through a screen surface, rotatable with the pumping element, by which screen the liquid 25 is brought to the final or ultimate degree of fineness at which time it is in counter-flow contact with the gas.

A further object of the invention is to provide the pumping element with special buckets, scoops or blades at the lower end thereof 30 which members gather the liquid from the underlying pan and start the same upwardly along the inner face of the pumping element thus assisting, to a greater or less degree, the 35 centrifugal action of the element in elevating the liquid.

A still further object of the invention is to provide a pan of special formation as to the 40 gas passages which extend therethrough and in so doing to produce channels or ways which effectively return the sprayed liquid to the center of the pan or to the zone of operation of the buckets or scoops carried at the lower end of the pumping element—and this 45 without any undue restriction of the gas flow which would lead to back pressure.

With these and other objects and advantages as will hereinafter appear, reference is had to the annexed drawings illustrative 50 of one embodiment of the invention, wherein;

Figure 1 is a vertical sectional elevation of the scrubber;

Figure 2 a similar view of one of the pumping elements and its cooperating screen or spray forming element;

Figure 3 a transverse horizontal section view of the pumping element taken on the line III—III of Figure 2;

Figure 4 a sectional plan view showing one of the liquid gathering pans or receptacles, 55 the section being on the line IV—IV of Figure 1; and

Figure 5 a side elevation thereof with parts broken away and shown in section.

In said drawings 1 denotes the shell or casing which in practice will be preferably made up from a series of sections as is usual in the art and secured together in any approved manner. The number of sections and consequently the height of the shell will of course 70 be dependent upon the desired capacity of the machine and while three pumping elements are shown in Figure 1 it is to be understood that a greater or less number may be employed.

At its lower end the casing is provided with a gas inlet 2 and a draw-off 3 while at the upper portion a gas outlet or off-take 4 is provided, the mouth of the latter being shielded from direct communication with the 80 spray chamber next adjacent by an inwardly extending shield or baffle plate 5.

Extending through the shell or casing is a vertically disposed shaft 6 supported at its upper end by any suitable form of bearing 85 designated by 7 and designed to be driven by suitable means as an electric motor 8. The lower end of the shaft extends into a bearing 9 which holds the shaft from lateral deflection.

The shell is divided into what may be termed a series of chambers produced by spaced pans, hereinafter specifically described, extending transversely of the shell or casing. Said chambers are designated generally by the reference numerals 10, 11, 12 and 13.

Inasmuch as the various pans and pumping and spraying elements are alike throughout the scrubber, a description of one set of such 100

elements will suffice. In the instant case three pans are shown, they being designated generally by 14, 14^a and 14^b. They are of a diameter substantially equal to that of the 5 interior of the shell and supported from the wall thereof by brackets 15.

The bottom 16 of the pan is provided with a centrally disposed opening through which the shaft 6 extends and an upstanding collar 10 17, spaced away from the shaft is provided at this point. The rim 18 is continuous and a weir plate 19 is adjustably secured thereto so that the depth of liquid in the pan may be regulated and determined.

15 Formed in the bottom 16 of the pan is a series of symmetrically disposed openings 20 generally segmental in outline and defined by walls extending upwardly from the bottom. The innermost wall is designated by 21, the 20 outer end whereof is in contact with and secured to the rim 18 of the pan. From this point it extends inwardly in a curve toward the center of the pan to a point 22 where it is recurved producing a wall section 23 25 which is substantially concentric with the center or axis of the pan.

The outer wall is designated by 24 and is preferably formed upon an unbroken curved line. At its outer end it is connected to the 30 wall section 21 at a point spaced inward of the rim 18 and from that point gradually curves inward away from the rim. There is thus formed between such wall 24 and rim 18 a passage-way or channel of gradually increasing width from the outer portion to the inner end where the channel discharges into what may be termed a central chamber or gathering chamber defined by the upstanding concentric wall sections 23. Thus it will be seen that there is formed upon the base or bottom 16 of the pan a series of channels 35 designated generally by 25 formed by the rim 18, the walls 24, and the sections 21 of the inner walls and that said channels discharge the liquid onto the central portion of the pan or into the central gathering space. As will be seen upon reference to Figures 1 and 5, the walls 21 and 24 will preferably be made higher adjacent their outer ends, or at those portions which are nearest the rim of the pan. 40 This however is not essential.

Secured at its upper edge in close contact with the inner wall of the casing above each pan is an inverted frusto-conical liquid gathering member or deflector 26, the lower inner edge whereof overlies and extends downwardly into the pan. Said member serves to return the sprayed liquid back to the pan and likewise prevents the gas from passing directly in an upward direction through the spaces between the outer edges of the pan and the wall of the apparatus.

The pumping and spray producing elements or means are best shown in Figures 2 and 3 and as they are alike in construction

a description of one will suffice, it being understood that there is one of such elements disposed in each chamber, other than 10, in operative relation to the liquid within the underlying pan.

70 The main body of the pumping and initial spraying element comprises an inverted frusto-conical member 27 and while the same is shown of a truly frusto-conical form the wall thereof may be curved.

75 Said body has secured to the upper end or portion thereof, by electric welding or otherwise, a horizontally disposed ring shaped member 28, to which is attached a spider frame 29 having a hub 30. The frame is secured to shaft 6 for rotation therewith by any suitable means as by wedge blocks 31 formed to engage the shaft and a pin carried thereby, as in Figure 2. This is of usual construction.

80 Body element 27 is provided with a series of openings 32 throughout its upper portion, said openings as shown, increasing in diameter toward the upper end thereof.

85 At its lower open end the pumping element or member 27 will be provided with a series of scoops or buckets which extend down into the liquid in the central or gathering portion of the pan. As illustrated, these scoops or buckets are each produced from sheet metal or plate 33 bent to form and secured at their advancing edges 34, as by welding, to the inner face of the member 27 into which the scoop may be said to merge.

90 As will be best seen upon reference to Figure 2, the advancing edge 34 of each scoop stands at an angle to the axis of shaft 6 or, in other words, inclines rearwardly with reference to the lower edge of the body 27, this assuming that the element 27 rotates clockwise as indicated by the arrow in Figure 3.

95 The lower end of each plate is bent inwardly at right angles, as at 35 forming a wall or flange which is inclined upwardly and rearwardly at substantially right angles 100 to the advancing edge 34 and inasmuch as the plates or bodies 33 are curved transversely the flange vanishes as it reaches the trailing inclined edge 36 of the plate.

105 As will be seen upon reference to Figure 2, the major portion of each plate extends below the lower edge of the body 27, the flanges or walls 35 being entirely so while the major portions of the advancing edges 34 are likewise positioned.

110 To maintain the overlapped and spaced bucket or scoop elements in position there is preferably employed a tie plate or member 37 of frusto-conical form which is welded to the upper edges of the flanges 35. Said member 37, in addition to tying the parts together and maintaining the buckets in their proper spaced relation, likewise assists in securing an even and distributed flow of the liquid 115

up along the surface of the pumping and distributing element 27.

Secured to the upper end of said element 27 and surrounding the same in spaced relation thereto is an annular screen 38 having a multiplicity of relatively fine perforations or openings 39 formed therein. Said openings will preferably be elongated, with the upper ends inclined rearwardly with reference to the direction of rotation of the screen and pumping element.

The screen which is of a depth sufficient to cover the openings 32 may be secured to the pumping and initial spray forming member 27 in any suitable manner, as by inwardly extending flanges 40 and 41, welded or otherwise secured to said member.

Liquid will be supplied to the various pans in any suitable manner as through a main 42, Figure 1, having valved branches 43 opening into the various chambers.

To prevent the gas which is forced into chamber 10 from passing upwardly about shaft 6 a casing 44 extending upwardly from the bottom of the apparatus to the pan 14 surrounds the shaft at this point. A cap piece 45 carried by shaft 6 overlies the upper end of the flange or collar 17 of the pan 14 and thus flow of gas upwardly about the shaft is cut off at this point.

It is thought that the operation of the apparatus will be apparent from the foregoing description but a brief resumé will be given. Assuming that the pans are filled with liquid and the laterals closed and gas is forced inwardly through the opening 2 and the shaft 6 is being rotated. Under these conditions the liquid would be picked up from each of the pans by the scoops or blades at the lower end of the frusto-conical pumping element, carried up along the inner face thereof outwardly through the openings 32 and through the openings 39 in the screen surface 38.

Centrifugal action causes the liquid to travel upwardly along the inner face of the member 27, through the openings 32, and through the openings 39. As it passes from the openings 39 it will be in the form of a fine rain or spray which is thrown outwardly toward the inner wall of the shell or casing 1 with which it contacts, running down said face, passes over the deflector or gatherer plate 26 and is returned to the pan. It then flows toward the center of the pan through the passages or channels 25 and again comes in the path of the scoops or blades by which it is again lifted and carried through the same cycle as just outlined.

At the same time the gas which is forced inwardly under pressure will pass through the openings 20 in the various pans and in passing from one set or series of openings to another the gas will of necessity have to pass through the outwardly thrown rain or spray

of liquid where intimate and close contact between the sub-divided liquid and the gas particles is effected.

The fineness of the spray may be readily determined by changing the size of the openings 32 and the openings 39 also to a greater or less extent by varying the speed of rotation by the pumping elements and the associated screens.

It will also be noted that the gas in the present apparatus does not pass through the screens but merely passes through the spray outward of the screens or between the screens and the wall of the casing. Thus the screens are not so likely to become clogged as would be the case where the gas passes through the screen surface along with the liquid.

Any gas which may pass upwardly between the outer portions of the pans and the inner face of the wall of the scrubber will of necessity be forced beneath the lower edge of the gathering element 26 and through the liquid in the pan, if in fact any gas passes at all beneath the lower edge of said gathering member.

It will, of course, be understood that the scrubber may be employed for various purposes and that it may be used for recirculation of the sprayed liquid by merely closing the laterals 43 after the pans have been filled, as above noted, or by leaving the upper lateral open secure a continuous counter-flow of the liquid and upcoming gas.

While I have described the buckets or scoops as being made of sheet steel, it will be appreciated, of course, that any suitable metal may be employed and that the elements may be secured in place by riveting or the like. So too, in the broader aspect of the invention, it is possible that the buckets may be formed integrally with the body of the member 27.

The uses to which the apparatus may be put are manifold but for the sake of brevity the term scrubber will be employed in the claims;—the use of such term, however, is not to be taken in any sense as a limitation.

What is claimed is:

1. In a centrifugal scrubber, the combination of a casing; a pumping member mounted therein, said member comprising a body element of inverted substantially frusto-conical form; a series of overlapping and spaced plates secured at their upper ends to the inner face of the lower portion of the body element, each of said plates at its lower end being formed with an inturned section, said section extending upwardly inclining rearwardly; and a frusto-conical cover plate overlying the upper edges of said inturned sections; and a pan-like receptacle underlying the lower ends of the series of plates aforesaid.

2. In a centrifugal scrubber the combination of a casing; a pan-like receptacle mounted therein, said receptacle having a series of openings extending upwardly therethrough; walls extending from the bottom

of the pan-like receptacle about each of said openings, the outer portion of said walls extending to the wall of the casing thereby forming channels for the return of liquid to the center of the pan; a shaft; a pumping element secured to the shaft and rotatable therewith, the lower end of the pumping element extending into the central portion of the pan; and means associated with said pumping element for spraying the liquid elevated by the pumping element outwardly against the wall of the shell or casing.

3. In a centrifugal scrubber, the combination of a shell or casing; a pan-like receptacle extending transversely thereof, said pan having a series of symmetrically disposed openings formed in the bottom thereof, said openings being bounded by upstanding walls arranged about each opening with at least one wall extending to the wall of the shell thereby forming a plurality of channels extending inwardly from the outer portion of the pan to the central portion thereof; a shaft, a pumping element secured to and rotatable with the shaft, the lower end of said element extending downwardly into the pan; and means associated with said pumping element for spraying the liquid outwardly therefrom.

4. In a centrifugal scrubber, the combination of a shell or casing; a pan-like element mounted therein, said pan being provided with a series of openings segmental in form and symmetrically disposed about the axis of the pan, said openings being defined by upstanding walls, the outer wall of each opening being formed upon a continuous curve which gradually extends inwardly toward the central portion of the pan while the inner wall of each of said openings is formed upon a broken curved line, the inner portion of which is substantially concentric with the axis of the pan whereby a series of channels is formed between the outer wall of the pan and the walls of the openings, which channels curve inwardly and discharge into the central portion of the pan; a shaft; a pumping element secured thereto, the lower end whereof extends into the central portion of the pan; means associated with the upper end of the pumping element for spraying the liquid raised thereby; and means for returning the sprayed liquid to the pan.

In testimony whereof I have signed my name to this specification.
